HEARING AID DEVICE

Emmanuel Christ Nicholides, Bronx, N. Y., assignor to Aurex Corporation, Chicago, Ill., a corporation of Illinois

Application July 11, 1940, Serial No. 344,853

8 Claims. (Cl. 179—107)

This invention relates to a bone conduction hearing aid device of the kind which includes a piezo-electric crystal.

The crystal per se may be of the Rochelle salt or similar type and such crystals are at the present time standard articles of commerce so will not be described in detail in this application, except to point out that when an electric field is impressed upon such a crystal, it distorts and when a series of electric waves of varying frequency and amplitude are applied, it is set in vibratory motion. Because of this characteristic, a piezo-electric crystal may be used to translate electric wave energy into mechanical vibratory motion.

In devices of this kind, sound waves are impressed upon a microphone or transmitter which serves to modify electric waves in accordance with the characteristics of the sound waves received and then these electric waves are conducted to the piezo-electric crystal which translates the electrical energy into mechanical vibratory energy for direct communication to the bone structure of the head.

A full description of the type of crystal used in devices of this kind and an electric circuit commonly used in such hearing aid devices, is shown and described in my Patent No. 2,045,403.

An object of the present invention is to construct a hearing aid device of the piezo-electric type designed so that a maximum of the vibratory energy of the crystal is communicated to the bone structure of the wearer.

It is also an object of this invention to communicate with a minimum of loss vibrations of such kind and quality as are found in ordinary speech and other common sounds.

A hearing aid device should be very small so that it will be inconspicuous when worn by the hard of hearing. On the other hand, the bone structure of the head possesses considerable mass and weight, and therefore, it is difficult to communicate the vibrations of the very small mass to the very large mass without changing the vibratory characteristics or limiting to a great extent the frequencies which can be transmitted, so it is an object of the present invention to produce a device which is small, light in weight and inconspicuous and yet powerful enough to transmit its vibratory energy to the head bone structure or other relatively heavy load, and especially to transmit those waves and frequencies which produce the speech sounds and more common sounds of every day life.

It is also an object of this invention to produce

a device which is simple and rugged in construction so that it will be durable and resist ordinary jars and impacts to which it might be subjected to in use or by accident.

Looking at the figures—

Fig. 1 is a plan view of the device with the cover removed;

Fig. 2 is a section through 2—2 of Fig. 1;

Fig. 3 is a section through 3—3 of Fig. 1;

Fig. 4 is a section through 4—4 of Fig. 1;

Fig. 5 is a section through 5—5 of Fig. 1;

Fig. 6 is a section through 6—6 of Fig. 1;

Fig. 7 is a plan view of the lever which is one of the elements of the device;

Fig. 8 is a section through 8—8 of Fig. 7;

Fig. 9 is a plan view of the diaphragm; and

Fig. 10 is a side view of the diaphragm.

Looking at Figs. 1 to 6. Fig. 1 is a base which may be made of plastic, hard rubber or other insulating material and on which the other elements of the device are mounted. A cover 2 is designed to cooperate with base 1 to make an enclosure for the various mechanical parts of the device and it is held in place on base 1 by means of screws 3 and 4.

Mounted on the left end of base 1 as viewed in Figs. 1 to 3, is a piezo-electric crystal of laminated form shown at 4. The left end of crystal 4 as viewed in Figs. 1 to 3, is clamped between clamping blocks 7 and 8. Block 7 is attached to base 1 and may even be cast or pressed from the same material and made an integral part thereof. Blocks 7 and 8 are designed to be held together by screws 10 and 11.

Between blocks 7 and 8 one end of crystal 4 is firmly held and the crystal is designed to extend outwardly from said clamping blocks in a more or less parallel relationship with the base 1 so that it is supported as a cantilever beam, supported at one end but free to move at the other. The clamping blocks 7 and 8 are preferably made of light weight material.

Also held between the blocks 7 and 8 is an end portion 16 of a lever 15 shown in detail in Figs. 7 and 8. The portion 16 is disposed under the crystal 4 directly on top of the shoulders of block 7. It is formed with a downwardly projecting lip 17 designed to strengthen it, and it serves to bridge over the space immediately above the head of the screw 18 so as to form a continuous flat surface to support the crystal 4.

Lever 15 when clamped in position projects outwardly from the clamping block 7 to the right as viewed in Fig. 2 in a more or less parallel relationship with the crystal 4 and the base 1.

It also is supported as a cantilever with one end held immovable while the other is free to move. It is formed with upwardly turned side pieces 21 which serve to give it strength and rigidity. From the side pieces 21 are turned out projecting ears 22 and 23. These as will be seen in Fig. 7, project transversely from the sides of the lever. They are designed to connect with curved arms 25 and 26 of diaphragm 27 (Figs. 9 and 10). A circular hole 28 through the center of lever 15 is furnished to accommodate the head of the central screw 30 which attaches button 31 to diaphragm 27.

Lever 15 is furnished with transverse ribs 33 and 34 to strengthen it. The more or less free end of lever 15 is connected to the free end of crystal 4 through the medium of two flexible springs 35 and 36 which support on their upper ends a collar 37 designed to firmly engage and hold the free end of crystal 4.

Diaphragm 27 is secured at ends 40 and 41 to base 1 by suitable screws 18 and 44 passing through holes 42 and 43. Screws 18 and 44 with washers 45 and 46 respectively, serve to hold the diaphragm 27 securely in place on the base 1. When so positioned, the curved arms 25 and 26 will engage the ears 22 and 23 of the lever 15 and may be joined thereto by soldering or by any other means.

Screw 30 passing through hole 45 in diaphragm 27, with the aid of a suitable washer 46 and a spacer 47, secures button 31 to diaphragm 27 but in spaced relation thereto, and so positioned that a portion of button 31 will project outwardly through aperture 49 in base 1.

Cover 2 is equipped with a pair of suitable conductors 50 and 50'. These conductors pass through the top of the cover 2 and turned over ends such as those shown at 51 and 52 of conductor 50, serve to hold the conductors firmly in place. The upper portion of cover 2 is equipped with a recess 55 having inwardly turned lips 56 and 57 under which a suitable terminal block may be inserted to make contact with conductors 50 and 50'.

Contact strips 60 and 61 are designed so that the right ends thereof (Figs. 1 to 3) will make contact with the left ends of conductors 50 and 50' when the cover is in place. Strips 60 and 61 are attached to the upper side of block 8 with screws 10 and 11 respectively. At the left end of the strips as viewed in Figs. 1 to 3, they are turned downwardly and each is formed into a terminal 63 and 64 to which the conductors from the crystal 4 are connected by soldering or otherwise.

When an electric current is sent through the conductor 50, it is transmitted through the strips 60 and 61 to the piezo-electric crystal 4, which is put in motion. This motion takes the form of a vibration having its maximum amplitude at the free end of the crystal (the right hand end as viewed in Figs. 1 to 3). This movement is communicated to lever 15 through the flexible springs 35 and 36. The motion of lever 15 in turn is communicated to diaphragm 27 from ears 22 and 23 to arms 25 and 26, and inasmuch as button 31 is connected to diaphragm 27, the button will be set in motion.

The free ends of both crystal 4 and lever 15 must of necessity move in an arc, but the longitudinal motion of the crystal is not communicated to the lever 15 because of the flexibility of arms 35 and 36, and in like manner, the longitudinal motion of lever 15 is not communicated to

diaphragm 27 because of the flexibility of arms 25 and 26 so that the vibratory movement imparted to button 31 is a straight line movement at right angles to the plane of the base 1.

5. The low frequency response of a piezo-electric crystal clamped at one end as described herein, can be increased by the addition of a weight on the free end thereof. However, this is accomplished at some sacrifice to the high frequency response because the additional weight increases the mechanical inertia of the vibrating crystal. In the present application, I have shown a crystal of tapered form, which construction results in an increase in the low frequency response without any loss of high frequency response. This is accomplished by constructing the crystal with an increasing taper extending from the clamped end thereof toward the free end. A crystal so formed has less stiffness than a rectangular crystal, and this increases the ratio of mass to stiffness without increasing the mechanical inertia of the system. Looking at Fig. 1, it is seen that the crystal 4 tapers from the end which is clamped between the blocks 7 and 8 toward the free end increasing in width from the clamped end toward the free end.

I wish it to be understood that I do not limit myself to the exact details of construction shown and described, as my invention is obviously capable of various modifications.

I claim:

1. In a hearing aid device, a base, a piezo-electric crystal mounted on said base with one end free to vibrate, a lever connected to said base and crystal, a diaphragm attached to said lever and a button connected to said diaphragm.
2. In a hearing aid device, a base, a piezo-electric crystal, means for attaching one end of said crystal to said base, a lever, means for attaching said lever to said base in close proximity to where said crystal is supported on said base and arranged to extend in the same direction as said crystal so that the free ends of said crystal and lever are near each other, flexible means for joining the free ends of said crystal and lever together, a diaphragm, means for connecting said diaphragm to said lever near the mid-point thereof, and a button on said diaphragm designed to transmit the vibration of said crystal to the load.
3. In a hearing aid device, a base, a piezo-electric crystal, means for clamping one end of said crystal to said base while maintaining them in substantially parallel relationship, a lever attached at one end thereof to said base and arranged in substantial parallelism with said base and crystal, a flexible member joining the free ends of said lever and crystal together, a diaphragm connected to said lever and a button on said diaphragm.
4. In a hearing aid device, a base, a piezo-electric crystal mounted on said base with one end free to vibrate, a flexible diaphragm, a button on said diaphragm adapted to communicate with a load, a lever for connecting said crystal and diaphragm so that vibratory movement of the crystal may be communicated to the latter.

5. In a hearing aid device, a base, a piezo-electric crystal mounted on said base so that one end thereof is free to vibrate, a lever connected to the free end of said crystal, a flexible diaphragm connected to said lever and a button connected to said diaphragm and adapted to communicate vibration of said diaphragm to a load.

6. In a hearing aid device, a base, a piezo-electric crystal mounted on said base so that one end

thereof is free to vibrate, a lever, a flexible connection between said lever and the free end of said crystal, a diaphragm, a flexible connection between said lever and said diaphragm, and a button on said diaphragm adapted to communicate vibration of said diaphragm to a load.

7. In a hearing aid device, a base, a piezo-electric crystal with one end clamped to said base and the other end free to vibrate, a lever disposed in substantial parallelism with said crystal and having corresponding ends clamped and free, a connection between the free ends of said crystal and lever which is flexible in a direction parallel

to the longitudinal axis of said crystal, a diaphragm, a connection between said lever and diaphragm which is flexible in a direction parallel to the axis of said diaphragm and adapted to communicate vibration thereof to a suitable load.

8. In a hearing aid device, a base, a tapered piezo-electric crystal, means for clamping the narrow end of said crystal to said base, a button extending through said base and adapted to carry 10 a load, and means for connecting the free end of said crystal and said button.

EMMANUEL CHRIST NICHOLIDES.
